UNITED STATES PATENT OFFICE

117,173

DESIGN FOR A TRANSPARENT CONTAINER FOR DISPLAYING LIVE INSECTS

James J. Gruenberg, Chicago, Ill.

Application February 21, 1939, Serial No. 83,146

Term of patent 3½ years

To all whom it may concern:

Be it known that I, James J. Gruenberg, a citizen of the United States, residing at Chicago, in the county of Cook and State of Illinois, have invented a new, original, and ornamental Design for a Transparent Container for Displaying Live Insects, of which the following is a specification, reference being had to the accompanying drawing, forming a part thereof.

Figure 1 is a top plan view of a transparent container for displaying live insects showing my design; and

Figure 2 is a front elevational view thereof.

I claim:

The ornamental design for a transparent container for displaying live insects, as shown.

JAMES J. GRUENBERG.
